UNITED STATES PATENT OFFICE.

JOHN KIBBLE, OF RICHMOND, VIRGINIA.

DESIGN FOR A WEATHER-VANE.

52,252.

Specification for Design.

Patented Aug. 6, 1918.

Application filed May 1, 1918. Serial No. 231,960. Term of patent 3½ years.

To all whom it may concern:

Be it known that I, JOHN KIBBLE, a citizen of the United States, residing at Richmond, in the county of Henrico and State of Virginia, have invented a new, original, and ornamental Design for Weather-Vanes, of which the following is a specification, reference being had to the accompanying drawing, forming a part thereof.

Figure 1 is a side elevation of the weather vane showing my new design.

Fig. 2 is a top plan view of the vane, and

Fig. 3 is a side elevation of the vane showing the side opposite to that illustrated in Fig. 1.

I claim:

The ornamental design for a weather vane as shown.

JOHN KIBBLE.
